UNITED STATES PATENT OFFICE.

LEWIS W. STROBER, OF WAUKEE, IOWA.

HORSE-COLLAR.

1,172,641.

Specification of Letters Patent. Patented Feb. 22, 1916.

Application filed May 6, 1915. Serial No. 26,379.

To all whom it may concern:

Be it known that I, LEWIS W. STROBER, citizen of the United States, residing at Waukeen, in the county of Dallas and State 5 of Iowa, have invented certain new and useful Improvements in Horse-Collars, of which the following is a specification.

My invention relates to horse collars and particularly to collars which are adjustable 10 to fit horses of different size; and it consists in certain peculiarities in construction and combination of parts to be hereinafter described and particularly pointed out in the claim.

15 In the drawings: Figure 1 is an elevation of a horse collar constructed in accordance with the present invention; Fig. 2 is a detail perspective view of that portion of the collar utilized to connect duplicate collar sections; and Fig. 3 is a similar view, the means utilized to join the collar sections at the base being shown.

Like numerals of reference designate like or corresponding parts throughout the several views.

Referring now to the drawings, 1—1 designates duplicate sections, each of a size and shape suitable for use. The sections 1 taper at each end, that connection provided 30 at the base of the collar and designated as an entirety by the numeral 2 consisting of a metal sleeve like structure 3 affixed to the collar section and flattened as indicated at 4, the flattened portion being provided with a 35 plurality of uniformly spaced aperaures 5, any one of which is adapted to receive an outturned lip or right angled extension 6 formed integrally with the flattened portion 7 of the sleeve like metal fastening portion 8 constituting the attaching means whereby 40 the last mentioned part is affixed to the other or opposite collar section 1. By passing the lip or extension 6 through one of the 45 mentioned apertures it is apparent that the sections 3 and 8 may be adjusted and thus held through the medium of a strap 9 affixed to the section 1 supporting the portion 3, the strap being buckled as indicated at 10 and passing through an eye 11 formed in 50 the lip or extension 6. A staple 12 is secured or made integral with the flattened portion 7 of the metal fastening device 8 to receive the yoke strap of the harness. Through the agency of the means just mentioned, the collar sections 1 are joined (ad-

justably) at the base or enlarged portion of the collar.

At the top of the collar a connecting portion designated as an entirety by the numeral 13 is provided, the said connecting portion consisting of a pliable padded strip 14 bifurcated at each end to provide straps designated respectively 15 and 16, the former, the strap 15, being adapted for buckling engagement as indicated at 17 with the padded portion of the collar 1 at each side thereof. Strap 16 is adapted for buckling engagement as indicated at 18 with the inner or rigid portion of the collar at each side thereof, the manner in which the connecting 70 element 14 is affixed at its opposite end being a duplicate at each side of the collar. An inner padded pliable strip 19 is affixed as at 20 to the strip 14 equi-distant from its ends, the inner strip being directly engageable with the neck of the animal to create a soft means of support. The inner strip is held in place by means of straps 21 affixed to the outer face of the mentioned strip, each strap passing about the collar 80 section 1 and embracing the aforementioned straps 15 and 16 to not only hold the strip 19 against lateral displacement, but also the strip 14 in proper place. Through adjustment of the straps 15 and 16 it is evident that the size of the collar may be varied to fit horses of different size; that adjustment may be obtained with facility and ease; and that subsequent to adjustment 85 the connecting portion 13 will positively 90 and effectually hold the sections 1 against relative lateral movement.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact 100 that various minor changes in details of construction, proportion and arrangement of parts may be resorted to, when required, without sacrificing any of the advantages 105 of my invention, as defined in the appended claim.

Having thus fully described my invention, what I claim as new and desire to secure by Letters Patent, is:—

In a horse collar, having duplicate sep. 110

arable side sections, a detachable neck shield for connecting the side sections, the said shield comprising a pair of soft flexible strips fastened together at a point equi-
5 distant from their ends, the upper strip being bifurcated at each end to provide a plurality of fastening straps, two buckles on each side section to engage with the straps thus formed to fasten said side sec-
10 tions between said strips, and a strap secured to the innermost strip adjacent each

end to pass transversely around the side section with which it is associated, said last mentioned strap being equipped with a fastening means.

15

In testimony whereof I affix my signature in presence of two witnesses.

LEWIS W. STROBER.
